UNITED STATES PATENT OFFICE.

SEBASTIAN RODRIGUEZ, OF FRANKLIN, LOUISIANA, ASSIGNOR OF ONE-HALF TO FRANCIS P. PERRET, OF FRANKLIN, LOUISIANA.

CULTIVATOR.

SPECIFICATION forming part of Letters Patent No. 712,096, dated October 28, 1902.

Application filed April 24, 1901. Renewed April 15, 1902. Serial No. 102,965. (No model.)

To all whom it may concern:

Be it known that I, SEBASTIAN RODRIGUEZ, a citizen of the United States, residing at Franklin, in the parish of St. Mary and State 5 of Louisiana, have invented certain new and useful Improvements in Cultivators; and I do hereby declare the following to be a full, clear, and exact description of the invention, such as will enable others skilled in the art to 10 which it appertains to make and use the same.

This invention relates to improvements in cultivators, and the invention is designed more particularly for use in the cultivation of cane; but it will be readily understood 15 that the cultivator is in many respects well adapted for other purposes, and I do not desire to be understood as limiting the invention to cane-cultivators only.

The object of the invention is to provide a 20 simple and efficient cultivator provided with means for thoroughly scraping off the excess dirt, covering the seed-cane or uncovering the row, for cleaning the row, taking the dirt off from the plant-cane, for shaving the stubble-cane, and for cleaning the stubble-row.

A further object of the invention is to provide a cultivator of the class described with a revolving scraper and small plows readily adjustable from or toward each other and 25 reversible for the purpose of covering or uncovering the row.

A further object is to provide the cultivator with horizontally-disposed revolving shavers.

Other objects of the invention are to simplify 35 the construction and render the various parts readily adjustable for the desired purposes.

With such and other objects in view the invention is embodied in the novel parts, arrangement and combinations of parts, hereinafter described, and particularly set forth 40 in the claims.

In the accompanying drawings is illustrated a construction embodying the invention; but 45 it is to be understood that the invention is not limited in its useful applications to this particular construction.

In the drawings, Figure 1 is an elevation of a cultivator embodying the invention, the 50 same being partly broken away for the purpose of better illustrating the invention.

Fig. 2 is a plan view of the cultivator illustrated in Fig. 1.

Referring to the drawings, A indicates a frame provided with axle-shaft B, upon which 55 are journaled wheels C C, the frame extending forward and constituting the draft devices for the cultivator, or, if preferred, draft means may be connected to the frame in any usual or desired manner. The frame may 60 also be of any desired or suitable construction; but I do not deem it necessary to describe the same particularly, as this invention relates more particularly to the construction and arrangement of the cultivating 65 devices, and any suitable frame can be readily constructed capable of the desired purpose of supporting and carrying the cultivating devices. Beneath the frame and hung therefrom by means of chains D D is what I term 70 the "cultivating-frame," (indicated at E.) It will be observed that the upper ends of the chains are connected to arms or the like f, connected to a cross-shaft F, which is mounted in suitable bearings on the frame A. 75 The shaft has rigidly secured thereto at a suitable point—for instance, at one end thereof—a lever F', by means of which the shaft is rocked in its bearings for the purpose of raising or lowering the chains and with them 80 the cultivating-frame. Suitable means are provided for holding the shaft in any desired adjustment, and for this purpose I provide the lever with a suitable pawl F'', adapted to engage with the teeth of a stationary segmental rack F''. The pawl is provided with 85 any suitable operating means—for instance, as indicated at F'''.

The cultivating-frame E is shown as composed of a central longitudinal beam E' and 90 two side beams E''. The side beams are adjustable toward and from the longitudinal beam by suitable instrumentalities. For instance, I have shown the front and rear transverse bars E''' rigidly secured to the central 95 beam and extending to each side thereof and provided with perforations e. These transverse bars extend through openings e' in the side beams E'', and keys or pins are passed through perforations in the side beams and 100 the perforations in the cross-bars. The forward end of the central longitudinal beam is

provided with forwardly-extending connecting-rods G, adapted to be secured at their forward ends to the frame or draft-rigging of the cultivator. Their connection with the 5 latter is not shown. The cultivating-frame is conveniently provided at its rear with suitable handles for the operator, the same being indicated at H.

At the forward end of the cultivating-frame 10 and suspended therefrom is a revolving scraper J, provided with radial blades j. This scraper is rotatively journaled in suitable brackets depending from the side beams E², and for the purpose of adjusting the scraper 15 up or down I have shown the brackets as composed of pivoted links K and brace-rods K', which are connected to the links at their lower ends or to the journal of the scraper and extend up beside the beams E². The 20 brace-rods K' are slotted and are adjustably secured at the desired adjustment to the beam by means of bolts or the like, k, passing through the slots into the beams. The shaft of the scraper should be sufficiently long to 25 permit the adjustment of the beams more or less away from the central longitudinal beam, and suitable collars or other devices may be employed, if necessary, on the scraper-journal to retain the scraper in its correct position and prevent side movement thereof. In 30 rear of the scraper are two small plows L, which, as will be observed, are supported by suitable standards L', depending from and secured in any preferred manner to the side beams E². The connection is such as to permit the plows being detached and shifted or 35 changed from one beam to the other for the purpose of throwing the moldboards inside or outside, so as to cover or uncover the row. 40 The plows being carried by the adjustable side beams are adjustable toward and from each other with the same.

M indicates a revolving colter, one provided for each plow and supported in correct relative position thereto by means of bearing-hangers M', connected adjustably to the side beams E²—for instance, by means of a bolt m, passing through one of a series of holes m' in the bearing-hanger and into the side 45 beam E².

Immediately behind and extending forward somewhat between the plows is a substantially triangular-shaped fluke N. This fluke is provided with a vertical standard N', which 50 for the purpose of adjustment is screw-threaded and passes through an opening in the central longitudinal beam E'. Suitable jam-nuts n are screwed onto the standard, one on each side of the beam, for securely holding 55 the fluke in adjusted position, as will be readily appreciated.

In front of the fluke N is a knife-shaped device N³, depending from the central beam. Behind the fluke N are two horizontal rotary 60 shavers O, which are rotatively mounted at the lower ends of vertical standards O', adjustably connected in any preferred manner

to the side beams E². The standards O' may be connected to the side beams similarly to the fluke N by means of nuts screwed onto 70 the standards O' and engaging the side beams. For the purpose of further strengthening and bracing the shaver-standards I have shown the same provided with suitable collars P, to which at each side are pivoted brace-rods P'. 75 The latter extend up beside and are adjustably secured to the beams E² by means of bolts passing through one of a series of perforations p in the brace-rods and into the side beams. 80

In rear of the shavers O and centrally between the same is a second cleaning-fluke Q, which, like the fluke N, is supported from the central beam E'. The connection is conveniently similar to that of the fluke N, and the 85 fluke is by means of this connection adjustable vertically.

It will be observed that the forward fluke N has its forward diverging sides vertical and curved or concaved, whereas the rear 90 fluke is triangular in shape and has its forward converging sides beveled downwardly from front to rear.

It is believed that from the above description the operation of the cultivator will be 95 readily apparent to those skilled in the use of such machines.

The machine and cultivator is intended to do all and any work in cane, corn, cotton, or other plants requiring a complete culture. It 100 will either cover or bare off, throw dirt to the plant, or remove it—in fact, is a full and complete cultivator and labor-saving machine.

Having thus described the invention, what I claim as new, and desire to secure by Letters 105 Patent, is—

1. In a cultivator, the combination with a main frame, of a cultivating-frame carried thereby, a revolving scraper J carried by said cultivating-frame, plows in the rear of said scraper, a fluke in the rear of said plows, and shavers depending from said frame back of 110 said fluke, substantially as described.

2. In a cultivator, the combination with a main frame, of a cultivating-frame carried thereby, a revolving scraper J carried by said cultivating-frame, plows in the rear of said scraper, a fluke in the rear of said plows, shavers depending from said frame back of 115 said fluke, and a second fluke in rear of said 120 shavers and centrally between the same, substantially as described.

3. In a cultivator, the combination with a main frame, of a cultivating-frame supported adjustably from the main frame, a revolving scraper J carried by said cultivating-frame, plows in the rear of said scraper, a fluke in the rear of said plows, shavers depending from 125 said frame back of said fluke, and a second fluke in rear of said shavers and centrally 130 between the same, substantially as described.

4. In a cultivator, the combination with a main frame, of a cultivating-frame supported adjustably from the main frame and hav-

ing laterally-adjustable beams, a revolving scraper J carried by said cultivating-frame, plows in the rear of said scraper, a fluke in the rear of said plows, shavers depending from 5 said frame back of said fluke, and a second fluke in rear of said shavers and centrally between the same, substantially as described.

In testimony whereof I affix my signature in presence of two witnesses.

SEBASTIAN ^{his} X RODRIGUEZ.
